UNITED STATES PATENT OFFICE.

CHARLES C. BLAKE, OF BROOKLINE, MASSACHUSETTS.

VAMP-TRIMMING MACHINE.

1,373,403.

Specification of Letters Patent.

Patented Apr. 5, 1921.

Application filed May 8, 1915. Serial No. 26,742.

To all whom it may concern:

Be it known that I, CHARLES C. BLAKE, a citizen of the United States, residing at Brookline, in the county of Norfolk and 5 State of Massachusetts, have invented a new and useful Improvement in Vamp-Trimming Machines, of which the following is a specification.

The present invention relates to machines 10 which are used in the manufacture of boots and shoes for preparing a shoe for a subsequent operation on the shoe bottom, and more particularly to machines for preparing a welted shoe for the sole laying operation.

In the system of welt shoe making devised by me the upper is lasted to the edge face of the insole with the free edge of the upper projecting substantially at right angles to 20 the exposed face of the insole. After the welt sewing operation, in which the welt, upper and insole are secured together by stitches which loop over tongues formed in the exposed face of the insole, it is desirable 25 to trim the upstanding edge of the vamp in order to prepare the welted shoe for the sole laying operation.

The object of the present invention is to produce a machine for use in my system of 30 welt shoe making which will economically and effectively trim the vamp of the welted shoe and thus prepare it for the sole laying operation.

To the accomplishment of this object and 35 such others as may hereinafter appear the features of the invention relate to certain devices, combinations and arrangements of parts hereinafter described and then set forth broadly and in detail in the appended 40 claims which possess advantages which will be apparent to those skilled in the art.

The various features of the present invention will be readily understood from an inspection of the accompanying drawings 45 illustrating the best form of the invention at present devised, in which,

Figure 1 is a left side elevation of the vamp trimming machine;

Fig. 2 is a plan, partly in section, of the 50 leader and its associated parts;

Fig. 3 is a sectional elevation of the jack and its supporting, actuating and guiding mechanisms;

Fig. 4 is a plan of the jack actuating and

guiding mechanisms beneath the jack supporting table;

Fig. 5 is a sectional elevation on the line 5—5, Fig. 3;

Fig. 6 is a front elevation of the rotary cutter and guard,

Fig. 7 is a right side elevation, partly in section, of the cutter and its guard, and

Fig. 8 is a detail showing the shape of the bearing face of the guard.

Referring to the drawings for a preliminary general description of the machine embodying the features of the present invention and the work performed thereby, the welted shoe having the free edge of its upper projecting substantially at right angles to 70 the exposed face of the insole is supported upon a jack which is actuated automatically to transfer the point of operation of the tool around the shoe. This tool comprises a rotary cylindrical cutter to trim the 75 upstanding edge of the vamp. The cutter is surrounded by a guard which is provided with a slot for the passage of the edge of the vamp to the cutter and is mounted to oscillate about the axis of the cutter to vary 80 the position of the slot in accordance with variations in the position of the edge of the vamp projecting from the curved shoe bottom.

In the illustrated embodiment of the invention the welted shoe hereinafter termed for convenience the "shoe" is mounted upon a jack 1 having a spindle 2 and a saddle 3 (Fig. 3). The spindle 2 is secured to a boss 4 formed between two vertical plates 6 rising from a base 7. The saddle 3 consists of a pad of yielding material mounted upon the upper end of a chambered post 8. The post 8 is mounted in a standard 9 and is guided to slide vertically therein by a screw 95 10 which is arranged to engage a slot 11 formed in the post 8. The saddle 3 is normally held elevated by a coiled spring 12 which is interposed between the bottom of the standard 9 and the top of the chamber 100 in the post 8. To permit the saddle to be forced upwardly to jack the shoe the post 8 carries a rack 13 which, when the saddle is under the influence of the spring 12, registers with an opening formed in a worm 15. 105 This worm is mounted in a housing 16, on a vertical shaft 17 journaled in the standard 9, and is provided with a handle 18 by

means of which the operative may engage the worm with the rack 13 and force the saddle 3 upwardly to jack the shoe. To permit the jack to accommodate different sizes 5 of shoes the standard 9 is mounted to slide on ways 19 formed on the plates 6. The base 7 is provided with runners 20 (Fig. 3) which are arranged to slide over the smooth 10 upper surface of a platen 21 (Figs. 1, 2 and 3). The platen is provided with a pair of dowels 22 (Fig. 2) arranged to engage sockets 23 (Fig. 4) formed in the upper surface of a bracket 24 which is bolted (Fig. 1) to the column 25 of the machine. The 15 platen 21 is additionally secured to the bracket 24 by means of a pair of screws 26 (Fig. 2).

In order to automatically slide the jack over the platen to transfer the point of operation of the tool around the shoe the jack is secured to a leader 27 (Figs. 1, 2 and 3) which is provided with a guiding flange 28 (Fig. 3) the internal periphery of which has the same contour as the edge of the sole 20 on the jack. In order to permit the peripheries of the sole and the leader to be vertically alined so that similar portions 25 of the sole and leader will move in unison throughout the operation of the machine 30 the leader is provided with a pair of buttonhole slots 29 (Fig. 2) which receive headed bolts 30 (Fig. 3) carried by the base 7 of the jack. With this construction the jack may be placed upon the leader by passing 35 the heads of the bolts 30 through the large ends of the buttonhole slots 29. The jack is then shifted on the leader until the edge of the sole is vertically alined with the internal edge of the leader. This movement 40 of the jack brings the shanks of the bolts within the small ends of the button-hole slots 29. To clamp the jack to the leader the ends of the shanks of the bolts are provided with pins 31 (Fig. 3) which 45 are engaged by the opposite ends of a leaf spring 32 arranged to embrace the shanks of the bolts. The spring is bowed to exert clamping pressure upon the bolts and thus clamp the jack to the leader by a triangular 50 cam 33 secured to a shaft 34 journaled in the plates 6 and actuated through a handle (not shown) carried by the shaft. The base 7 carries a pair of pins 36 which act as fulcrums 55 for the leaf spring 32 during the bowing thereof.

The leader is actuated to transfer the point of operation of the tool around the shoe by a gear 37 which engages rack teeth 38 formed on the exterior of the guiding 60 flange 28. The gear 37 is secured to the upper end of a vertical shaft 39 journaled in bearings formed in the bracket 24 and column 25. The shaft 39 is driven from a horizontal shaft 40 (Fig. 1) journaled in the 65 column 25, through a worm 41 on the shaft

40 which meshes with a worm wheel 42 on the shaft 39. The shaft 40 loosely carries a pulley 43 which is driven from a motor 44, mounted on the base of the column 25, through a belt 45. The pulley 43 carries a 70 friction disk which is arranged to be engaged by a similar disk 46 splined on the shaft 40. In order to shift the disk 46 on the shaft 40 and thus clutch the pulley 43 to the shaft 40 the disk 46 is provided with 75 a peripheral groove 47 which is engaged by a pair of blocks 48 carried by the vertical arm of a bell crank lever 49 pivoted on a bracket 50 on the column 25. The horizontal arm of the bell crank lever 49 is pivoted to the upper end of a rod 51 which slides freely through a sleeve 52 on the column 25. The lower end of the rod 51 is pivoted to a treadle 53. With this construction pressure 80 on the treadle slides the disk 46 on the shaft 40 into engagement with the pulley 43 and thus clutches the shaft 40 to the source of power. The disk 46 is normally held away from a pulley 43 and in contact with a braking surface 54, formed on the bracket 50, by 85 a spring 55 coiled around the rod 51 and interposed between the bell crank lever 49 and the sleeve 52.

In order to swing the jack laterally as the point of operation of the tool is transferred 90 around the shoe to maintain the edge of the shoe sole in proximity to the tool in the line of feed the guiding flange 28 on the leader is engaged by a pin 56 (Figs. 2, 3 and 4) arranged to engage inside the flange and by 100 guide rolls 57 and 58 arranged to engage outside the flange. The guide pin 56 is formed upon the upper end of a vertical rod 59 which is loosely mounted in a bearing formed in the bracket 24. The rod 59 carries a plane surfaced block 60 which is provided with a roll 61 embraced by a cam slot 62 (Figs. 3 and 5) formed in a vertical flange 63 of a horizontal slide 64 slidably mounted in the bracket 24. The slide 64 is 105 connected to an arm 65 (Figs. 1 and 5) projecting from a rock shaft 66 journaled in the column 25. A second arm 67 projecting from the rock shaft 66 is provided with a handle 68 by means of which the slide 64 110 may be actuated to cause the cam slot 62 to act upon the roll 61 and depress the guide pin 56 below the guiding flange 28 and also below the surface of the platen. The guide pin 56 is eccentrically mounted on the rod 115 59 to permit it to traverse the short curve at the toe of the leader and is made semi-circular in the manner illustrated in Fig. 2 to avoid all danger of interference with the heads of the bolts 30.

In order to hold the leader down upon the platen the exterior edge of the flange is beveled as shown at 69 (Figs. 3 and 5). This beveled surface is engaged by the frusto-conical guide rolls 57 and 58. By engag- 120 125 130

ing the flange 28 the guiding devices 56, 57 and 58 act to swing the jack laterally about an axis tangential to the edge of the shoe sole in order to bring the upstanding edge 5 of the vamp into the desired position with relation to the line of feed. In order to enable the rolls 57 and 58 to engage the flange at all times without binding as they traverse the reverse curves of the flange at the shank 10 and around the toe the guide rolls 57 and 58 are journaled in a slide 70 (Figs. 2, 4 and 5) mounted to slide in a guideway 71 formed in the bracket 24 and are actuated in a direction to press the guide rolls 57 and 58 15 against the flange 28 by means of a spring 72 (Fig. 2). It has been proposed heretofore to connect the spring 72 directly to the slide 70. With this construction it is found that the pressure is decreased during the 20 traverse of the rolls along a convex curve, such as at the toe of the leader, and that the pressure is increased during the traverse of the rolls along a concave surface, such as at the shank of the leader. Owing to the great 25 arc through which it is necessary to swing the comparatively heavy leader and jack supported thereby during the traverse of the rolls around the toe it is found that with the construction referred to great pressure 30 is brought to bear upon the rolls during their traverse of the toe. As the spring is pressing the rolls against the leader during their traverse of the toe with its minimum pressure there is a tendency for the leader 35 to move away from one of the rolls thus changing the axis about which the work swings. As it is desirable to swing the work constantly about an axis tangential to the edge of the insole of the shoe the spring 72, 40 instead of being directly connected to the slide 70, is connected to the slide through a lever 73 arranged to vary the leverage inversely to variations in the tension on the spring. That is, the pressure on the rolls 45 is increased during their traverse of the toe of the leader and is decreased during their traverse along the shank of the leader. By increasing the pressure on the rolls during their traverse of the toe the leader is pre- 50 vented from moving away from one of the rolls. As the leverage of the swinging work is neutralized during the traverse of the rolls along the shank of the leader the pressure on the rolls may be decreased during their 55 traverse of the shank thus reducing the friction to a minimum. The lever 73 is pivoted at one end to the bracket 24. At its other end the lever is pivoted to a block 74 which loosely receives a rod 75 pivoted to an ex- 60 tension of the bracket 24. The spring 72 is coiled around the rod 75 and is interposed between the block 74 and a shoulder 76 on the rod. The lever 73 is pivoted intermediate its ends by a short link 77 to the slide 65 70. From an inspection of Figs. 2 and 4

it will be readily seen that the link 77 is connected to a rigid arm, that is an arm not compressible longitudinally, of a toggle the other arm of which is yielding. With this construction the pressure of the rolls on the 70 leader is at its minimum when the toggle approaches its made position and is at its maximum when the toggle approaches its broken position. As the slide is positioned farther to the right (Figs. 2 and 4) during 75 the traverse of the rolls around the toe of the leader than during the traverse of the rolls along the shank of the leader it will be obvious that, with the improved construction referred to, the pressure on the rolls 80 will increase during their traverse of the toe and decrease during their traverse of the shank. While the rigid arm of the toggle is shown in the illustrated embodiment of the invention as a lever of the second order 85 it will be readily understood by those skilled in the art that levers of the other orders may comprise the rigid arm of the toggle. To withdraw the guide rolls 57 and 58 from the guiding flange at the same time as 90 the guiding pin 56 is withdrawn therefrom the slide 64 is provided with a cam slot 78 (Figs. 2 and 3) which embraces a roll 79 carried by the slide 70. With this construction a downward movement of the handle 95 68 simultaneously depresses the guide pin 56 and withdraws the guide rolls 57 and 58 from the flange. It will be noticed from an inspection of Figs. 2 and 4 that the cam slot 78 is wide enough to permit the roll 79 100 to move therein as the guide rolls 57 and 58 yield to the curves of the leader. In order to hold the slide 64 in a normal operative position with the handle 68 elevated the arm 65 is pivoted to a rod 80 which passes 105 loosely through a lug 81 on the column 25. Interposed between the lug 81 and a shoulder 82 on the rod is a spring 83 which is coiled around the rod. The movement of the slide 64 is limited in both directions by a 110 pair of pins 84 and 85 (Fig. 2) arranged to alternately engage opposite sides of the bracket 24.

The tool for trimming the vamp comprises a cylindrical cutter 86 (Fig. 7) which is 115 threaded upon a carrier 87 shrunk upon a hollow shaft 88. The cutter is locked against accidental rotation on the carrier by one or more plates 89 secured to the carrier 87 and engaged with slots 90 formed in 120 the back edge of the cutter. The shaft 88 is journaled in bearings 91 formed in a yoke 92 which is pivoted on studs 93 secured to the arms of a yoke bracket 94 secured to the top of the column 25. The studs 93 are 125 located in a horizontal plane having a height above the platen substantially equal to the mean height of the shoes supported on the platen. With this construction the point of 130 operation of the cutter is maintained sub-

stantially at the lateral turning axis of the jack notwithstanding variations in the slope of the shoe bottom. The pivotal movement of the yoke 92 is limited in both directions 5 by a pin 95 which works in a slot 96 formed in a strap 97 pivoted to the yoke 92. The shaft 88 is driven at a high speed from the motor 44 by a round belt 98 which passes over a pulley 99 on the motor shaft and a 10 pulley 100 on the shaft 88. The belt 98 also engages the periphery of a pair of idlers 101 journaled on the yoke bracket 92.

In order to guard the operative and cutter from injury the cutter is surrounded by a 15 guard 102 (Figs. 1, 6 and 7) which is pivoted to oscillate about the axis of the cutter on a pin 103 supported by a guard carrier 104. The carrier 104 is mounted in a slot 105 formed in a block 106 which is pinned to the 20 front end of a rod 107 forming an extension of the yoke 92. The guard carrier 104 is pivoted on a pin 108 to permit the guard to swing away from the cutter when it is desired to expose the cutting edge for inspection 25 or to grind the cutting edge. The guard is locked in position surrounding the cutter by a spring-pressed pin 109 mounted within a chamber 110 on the block 106 and arranged to engage a hole 111 formed in the carrier 30 104. The pin 109 may be withdrawn from engagement with the hole 111 by a finger-piece 112 and then locked in its withdrawn position by rotating the finger-piece 112 to place a pin 113, normally engaged with a 35 slot 114 formed in the chamber 110, upon the top of the chamber.

The guard 102 is provided with a slot 115 for the passage of the upstanding edge of the vamp to the cutter and with a pair of feet 116 and 117 which straddle the edge of the vamp and engage the welt and exposed 40 face of the insole, respectively. The foot 116 is provided with an edge gage 118 (Fig. 8) which engages the outside edge of the welt. 45 The guard 102, above the feet 116 and 117, is beveled, as at 119, to insure the free passage of the work through the slot 115. The feet 116 and 117 press upon the welt and insole 50 during the feed of the work and automatically adapt themselves to the contour of the work engaged thereby and thus tip the guard about the axis of the cutter to insure that the slot 115 will follow the varying 55 positions of the edge of the vamp on the curved shoe bottom. The oscillating movement of the guard 102 is limited in both directions by a pair of pins 118^a on the guard arranged to engage the opposite sides of the guard carrier. The guard 102 also 60 acts as a gage for controlling the height above the shoe bottom at which the vamp is trimmed by the cutter. To this end the feet 116 and 117 are provided with a bearing edge 120 (Figs. 6, 7 and 8) arranged in the 65 plane of the cutting edge of the cutter. The

feet 116 and 117 are beveled in advance of the bearing edge 120, as at 121 (Figs. 6, 7 and 8) to permit the feet to travel up a slope on the shoe bottom without affecting the depth of cut. To permit the guard 102 to ride down a slope on the shoe bottom the feet 116 and 117 are also beveled, at 122. The bevel 122 need not be as great as the bevel 121 owing to the incidence of the cutter (Fig. 1). With this construction the bearing edge 120 always rests upon the shoe bottom notwithstanding the varying slopes on the shoe bottom. The weight of the cutter, guard and associated parts is counterbalanced by a weight 123 which is carried 80 upon a rod 124 secured to the yoke 92.

To operate the machine the operative starts the motor 44 and then depresses the handle 68 thus separating the guiding rolls 57 and 58 and guiding pin 59 to permit the 85 meshing of the gear 37 with the teeth 38 on the guiding flange 28. The handle 68 is then elevated to grip the guiding flange between the guide pin and rolls. The operative then draws the cutter and its guard down upon the work upon which it rests under the influence of gravity. The treadle 53 is then depressed thus throwing the mechanism for actuating the jack into operation to transfer the point of operation of 90 the cutter around the work. During the transfer of the cutter around the work the feet 116 and 117 automatically adapt themselves to the contour of the work thereby turning the guard about the axis of the 95 cutter to vary the position of the slot 115 in accordance with the varying positions of the upstanding edge of the vamp on the curved shoe bottom. The jack continues to move until the gear 37 runs out of engagement with the teeth 38 into a slot 125 formed in the heel end of the leader which permits the gear 37 to continue to rotate without feeding the work. When the jack automatically stops in the manner described 100 the cutter and treadle are elevated and the handle 68 is depressed to permit the removal of the trimmed shoe and the insertion of another welted shoe. The scrap removed from the shoes by the cutter is removed by connecting the hollow end of the shaft 88 to an 105 exhaust system.

While the primary object of the present invention is directed narrowly to my improved system of making welt shoes it is not 110 to be understood as limiting the scope of the claims, where the context otherwise permits, to a vamp trimming machine for trimming the vamp of a Blake welt shoe, as it will be apparent to those skilled in the art that certain features and combinations of parts hereinbefore described are well adapted to make Goodyear welt shoes or, in fact, for general 115 use in the manufacture of shoes.

It will be clear to those skilled in this 120

class of machines and with the general objects of the present invention in view, that changes may be made in the details of structure, the described and illustrated embodiment thereof being intended as an exploitation of its underlying essentials, the features whereof are definitely stated in their true scope in the claims herewith.

What is claimed as new, is:—

- 5 1. A vamp trimming machine, having, in combination, a support for a shoe, a knife to trim the edge of the vamp of the shoe, and means for relatively actuating the knife and support to transfer the point of operation of the knife around the shoe in a progressive manner along one side of the shoe around an end curvature thereof to the other side of the shoe, substantially as described.
- 10 2. A vamp trimming machine, having, in combination, a support for a shoe, a knife to trim the edge of the vamp of the shoe, and means for actuating the support to transfer the point of operation of the knife around the shoe in a progressive manner along one side of the shoe around an end curvature thereof to the other side of the shoe, substantially as described.
- 15 3. A vamp trimming machine, having, in combination, a shoe supporting jack, a cylindrical cutter to trim the edge of the vamp, and means for relatively actuating the jack and cutter to transfer the point of operation of the cutter around the shoe, substantially as described.
- 20 4. A vamp trimming machine, having, in combination, a longitudinally movable and rotatable support for a shoe, a knife to trim the edge of the vamp of the shoe, and means for actuating the support to transfer the point of operation of the knife around the shoe, substantially as described.
- 25 5. A machine for preparing a welted shoe for the sole laying operation, having, in combination, a rotary cutter, and a guard therefor mounted to turn automatically under the pressure of the work about the axis of the cutter, substantially as described.
- 30 6. A machine for preparing a shoe for a subsequent operation on the shoe bottom, having, in combination, a knife to trim the upstanding edge of the work, and a guard for the knife provided with a pair of feet arranged to straddle the upstanding edge of the work and mounted to turn automatically under the pressure of the work about the axis of the cutter, substantially as described.
- 35 7. A machine for preparing a shoe for a subsequent operation on the shoe bottom, having, in combination, a knife to trim the upstanding edge of the work, and a guard for the knife provided with a pair of feet arranged to straddle the upstanding edge of the vamp and engage the welt and insole and mounted to turn automatically under the

pressure of the work about the axis of the cutter, respectively, substantially as described.

8. A machine for preparing a shoe for a subsequent operation on the shoe bottom, 70 having, in combination, a rotary knife to trim the upstanding edge of the work, a pivotally mounted guard for the knife, and a plurality of feet on the guard arranged to engage the work and adapt themselves to 75 the curvature thereof and swing the guard about the axis of the knife, substantially as described.

9. A machine for preparing a shoe for a subsequent operation on the shoe bottom, 80 having, in combination, a work support, a knife to trim the upstanding edge of the work, means for relatively actuating the support and knife to transfer the point of operation of the knife around the work, a 85 pivotally mounted guard for the knife, and a plurality of feet on the guard arranged to engage the work and adapt themselves to the curvature thereof and swing the guard about its axis during the transfer of the tool 90 around the work, substantially as described.

10. A machine for preparing a welted shoe for the sole laying operation, having, in combination, a cutter for removing the surplus stock on the shoe bottom, and a guard 95 therefor mounted to automatically adapt itself to the contour of the work, substantially as described.

11. A machine for preparing a welted shoe for the sole laying operation, having, 100 in combination, a cutter for removing the surplus stock on the shoe bottom, a guard for the cutter having a slot formed therein for the passage of the surplus stock to the cutter, and a pair of feet on the guard arranged to straddle the surplus stock and vary the position of the slot in accordance with variations in the position of the surplus stock, substantially as described.

12. A machine for preparing a welted 110 shoe for the sole laying operation, having, in combination, a work support, a cutter for removing the surplus stock on the shoe bottom, means for relatively actuating the support and cutter to transfer the point of 115 operation of the cutter around the work, a guard for the cutter having a slot formed therein for the passage of the surplus stock to the cutter, and a plurality of feet on the guard arranged to engage the work and 120 adapt themselves to the curvature thereof and vary the position of the slot in accordance with variations in the position of the surplus stock, substantially as described.

13. A machine for preparing a welted 125 shoe for the sole laying operation, having, in combination, a cutter, and a guard therefor provided with a slot for the passage of the work to the cutter mounted to shift automatically under the pressure of the work 130

to vary the position of the slot in accordance with variations in the position of the work, substantially as described.

14. A shoe machine, having, in combination, a rotary cutter, a guard therefor mounted to oscillate about the axis of the cutter, a guard carrier and devices carried by the guard and coöperating with the carrier for limiting the oscillating movement of the guard, substantially as described.

15. A shoe machine, having, in combination, a rotary cutter, an independent support, a guard carrier pivoted thereon, and a guard for the cutter mounted to oscillate upon the carrier about the axis of the cutter, substantially as described.

16. A shoe machine, having, in combination, a rotary cutter, an independent support, a guard carrier pivoted thereon, a guard for the cutter mounted to oscillate upon the carrier about the axis of the cutter, and means for limiting the oscillating movement of the guard, substantially as described.

17. A shoe machine, having, in combination, a rotary cutter, an independent support, a guard carrier pivoted thereon, a guard for the cutter mounted to oscillate upon the carrier about the axis of the cutter, and means for locking the carrier upon the support, substantially as described.

18. A shoe machine, having, in combination, a platen, a support for a shoe mounted thereon, and a tool for operating upon the shoe mounted to tip about an axis located in a horizontal plane having a height above the platen substantially equal to the mean height of the supported shoes, substantially as described.

19. A shoe machine, having, in combination, a platen, a support for a shoe mounted thereon, and a tool for operating upon the shoe mounted to tip about an axis of non-intersection with the work and located in a horizontal plane having a height above the platen substantially equal to the mean height of the supported shoes, substantially as described.

20. A shoe machine, having, in combination, a tool, a shoe supporting jack, a leader connected thereto, and driving mechanism coöperating with the leader for actuating the jack to transfer the point of operation of the tool around the shoe, said leader being constructed and arranged to automatically stop the transfer of the point of operation of the tool without stopping the driving mechanism, substantially as described.

21. A shoe machine, having, in combination, a shoe support, and a cutter mounted on a horizontal axis to engage the work and rise and fall under the influence of the work

to automatically adapt itself to the height of the work at the point of operation, substantially as described.

22. A vamp trimming machine, having, in combination, a cutter, a depth gage therefor mounted to embrace the free edge of the vamp, and means permitting the gage to ride over the varying slopes of the work without variations in the depth of cut, substantially as described.

23. A shoe machine, having, in combination, a cutter and a depth gage therefor provided with beveled faces on its bottom which meet in a line arranged to bear uniformly on the shoe bottom, substantially as described.

24. A shoe machine, having, in combination, a cutter, a guard therefor, and a plurality of feet on the guard arranged to engage the work, each of said feet being provided with beveled faces which meet in a line arranged to bear uniformly on the shoe bottom, substantially as described.

25. A shoe machine, having, in combination, a shoe support, a cutter, and a guard therefor mounted to engage the work and move under the influence of the work laterally and vertically to automatically adapt itself to the curvatures of the work at the point of operation, substantially as described.

26. A shoe machine, having, in combination, a shoe support and a cutter mounted on a shaft inclined to the work having relative rising and falling movements under the pressure of the work to automatically adapt the cutter to the height of the work at the point of operation.

27. A machine for preparing a welted shoe for the sole laying operation, having, in combination, a support for a welted shoe and rotary operating means for trimming the upstanding skirt of the upper down to the plane of the insole.

28. A machine for preparing a welted shoe for the sole laying operation, having, in combination, a support for a welted shoe, operating means for trimming the upstanding skirt of the upper down to the plane of the insole, and means for relatively actuating the support and operating means to transfer the point of operation of the operating means around the shoe from one breast corner to the other.

29. A machine for preparing a welted shoe for the sole laying operation, having, in combination, a knife for trimming the upstanding skirt of the upper down to the plane of the insole and a guard for the knife provided with a pair of feet arranged to straddle the upstanding skirt.

CHARLES C. BLAKE.
